HITCH FOR ROAD GRADERS AND THE LIKE

James Markoe, St. Paul, Minn., assignor to Foote Bros. Gear and Machine Corporation, Chicago, Ill., a corporation of Delaware

Application October 28, 1937, Serial No. 171,425

2 Claims. (Cl. 280—33.10)

The present invention relates to hitches for road graders and the like.

The primary object of the invention is the provision of a hitch which may be attached to a prime mover, such as a truck or tractor, and which permits of controlled lateral movement of a drawn implement which may be a road grader or other device.

The invention as herein described and illustrated is applied to a road grader. It is apparent, however, that it may be applied to other instrumentalities with equal effectiveness.

In the construction and maintenance of roads the prime mover is generally a truck or tractor which pulls a grader or other device which has well known functions. Heretofore the hitch or connection between the prime mover and the grader has generally been of such character that lateral movement of the grader with respect to the surface being graded is controlled by lateral movement of the prime mover and such endwise movement of the grader blade as is permissible in the construction of such machines.

Such arrangement of the grader and its source of power has a number of disadvantages. For instance, it is generally desirable that when the grader is being used to grade the shoulder of a concrete highway that the prime mover operate upon the concrete and the grader is so connected to the prime mover as to be offset relative thereto so that it will operate upon the shoulder of the road. Since there are obstructions along the shoulders, such as bridges, culverts and the like, it is necessary with the arrangement just described that the prime mover move beyond the center of the concrete so as to permit the blade of the scraper to clear such obstructions as may be present along the shoulder. Except on very wide roads the equipment blocks the road completely thus creating a dangerous situation.

Furthermore, since the shoulder of the road varies in width it is desirable, from an operating standpoint, to be able to shift the relative position of the grader and the prime mover easily and to any desired amount without the necessity of disengaging the grader from the prime mover. This feature, which is made possible by the present invention, is not only important in shoulder grading but in other forms of grading and as applied to various instrumentalities used in the construction and maintenance of roads such, for example, as snow plows.

For purposes of illustration there is shown in the accompanying drawings and described in the specification a preferred form of the invention.

Objects and advantages of the invention other than those above set forth will be obvious to those skilled in the art and it is to be understood that the invention is not to be unnecessarily limited by the specification and drawings, its true scope being defined by the appended claims. 5

Referring to the drawings:

Fig. 1 is a view in side elevation showing a portion of a prime mover, schematic diagram of a grader and in detail the preferred embodiment 10 of the hitch;

Fig. 2 is a schematic top plan view of a prime mover and grader, the position of the grader being shown for normal operation in full lines and in dotted lines when it must pass an obstruction; 15

Fig. 3 is a detailed view of the hitch member proper taken in side elevation;

Fig. 4 is a top plan view of the hitch;

Fig. 5 is a section taken on the line 5—5 of Fig. 4; and

Fig. 6 is a section taken on the line 6—6 of Fig. 5. 20

In the drawings the reference character 11 indicates the prime mover, such as a tractor or truck, the frame of which is indicated by the reference character 12. Attached to the back of the frame is an angle member 13 which is spaced from the frame 12 by a plurality of spacing members 14 and secured to the frame 12 by the bolts 15 which pass through the spacing members 14. The 30 angle member 13 is of unusual shape in that the bottom arm 16 thereof is bent near the outer edge at an obtuse angle to provide an upwardly projecting portion 17, as is apparent from Figs. 3, 4 and 5 of the drawings. 35

The portion 17 of the angle member 13 is provided with a plurality of slightly elongated holes or slots 18 which are adapted to engage the teeth 19 of the spur pinion 20 as shown in detail in Figs. 5 and 6. The grader or other drawn instrumentality is slidably connected to the angle member 13 by means of a bracket 21 which has secured to it extensions 22 and 23 that engage the angle member 13. The extension 22 is shaped to conform to the bottom portions 16 and 17 of the angle member and is provided at its extreme end with a block 24 that engages the upstanding portion of the angle member. The extension 23 is of substantially the same shape as the extension 22 and is provided at its extreme end with a block 25 50 which engages the angle member 13 and a stop block 26 which engages the opposite face of the angle member. 45

It will be apparent from the preceding paragraph that the bracket 21 and its extension mem- 55

bers so encompass and engage the angle member that when pulling force is applied to the angle member it will be transmitted to bracket 21 and due to the shape of the extension 22 in relation to the portions 16 and 17 of the angle member and the presence of the stop 26 forward movement of the bracket 21 relative to the angle member 13 is prevented. Lateral relative movement between the angle member and the bracket is easily accomplished, however, the bracket riding upon the angle member.

The bracket 21 is connected to the implement being drawn through the swivel connection 27 which includes the clevises 28 and 29, the latter permitting of such rotary misalignment as may of necessity take place between the drawn implement and the prime mover. The clevises 28 and 29 merely consist of bifurcating members which are secured in place and permitted to pivot about the pins 30 and 31 respectively, the latter pin passing through a hole in the bracket 21.

Relative lateral movement between the bracket and the angle member is accomplished through means of the pinion 20 and its connecting shaft members which are rotated by the hand wheel 32 as shown in Fig. 1. The connecting shaft members include a universal 33 which has attached to it the shaft 34, the opposite end of which shaft is attached to the universal 35. The universal 35 is driven by the shaft 36 on the other end of which shaft is mounted the hand wheel 32. It will be apparent that upon rotation of the hand wheel 32 rotary movement is imparted to the pinion and since the pinion 20 is mounted in the bracket 21 and its teeth engage with the holes 18 of the angle member the relative lateral positions of the angle member and the bracket may be conveniently and readily changed, thereby shifting the relative position of the drawn implement to the prime mover.

Since it is desirable, except during time of adjustment, that the prime mover and the drawn instrument be held in predetermined position a locking pin 37 is provided as shown in Figs. 1, 2, 3 and 4. The locking pin 37 is slidably mounted in the bracket 21 and is controlled by the bell crank lever 38 which is pivoted to the bracket 21. Connection between the bell crank lever 38 and the pin 37 is made through pin 39 which projects from the pin 37 and passes through an elongated opening 40 in the lower leg of the bell crank lever 38. The pin 37 is of such shape as to pass through the openings 18 in the angle member and thence into an opening 41 in the bracket thus locking bracket and angle member against relative movement.

The pin 37 is moved into and out of locking position through means of the bell crank lever 38 and the connecting links 42 and 43, shown in Fig. 3, and the link 44 shown in Fig. 1. The link 44 ends in a handle member 45. The linkage 42, 43 and 44 is held in position by suitable supporting members 46 and 47.

Movement of the link 44 endwise through operation of the handle 45 causes the pin 37 to be raised or lowered at the will of the operator. When it is desired to shift the position of the drawn implement relative to the prime mover the pin 37 is disengaged from locking position by pulling the handle member 45 toward the operator; the hand wheel 32 may then be rotated to adjust the position of the bracket on the angle member. When the desired relationship has been established the locking pin is then dropped into place by forward movement of the handle 45.

It will be apparent that while the hitch mechanism is shown as being controlled from the drawn implement that should it be desirable that the same be controlled from the prime mover it will merely be necessary to change the arrangement of the linkage and universals in an obvious manner so that they may be operated from the prime mover.

I claim:

1. A hitch of the character described comprising an angle member, one arm of said angle member having a portion thereof bent at an obtuse angle, regularly spaced openings in the last mentioned portion of said arm, a bracket slidably mounted on said angle member, means for moving said bracket relative to said angle member and means for holding said angle member and said bracket in predetermined positions, the last mentioned means comprising a pin mounted on one of said members and capable of being passed through a hole in one of said members and into a stop opening in the other of said members.

2. A hitch of the character described comprising a fixed member, a portion projecting from said fixed member at an obtuse angle thereto and having regularly spaced openings therein, a bracket slidably mounted on said fixed member, means for moving said bracket relative to said fixed member, said means comprising a gear mounted at right angles to said projecting portion, the teeth of said gear extending into said openings, means for driving said gear and a swivel joint secured to said slidably member adapted to be directly connected to the frame of an implement being drawn.

JAMES MARKOE.
